CLAIM

The ornamental design for a power transfer switch, as shown and described.

DESCRIPTION

FIG. 1 is front perspective view of a power transfer switch illustrating our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a right perspective view thereof.

The broken line portion of the figure drawings is included to show unclaimed subject matter only and forms no part of the claimed design.

UNITED STATES PATENT AND TRADEMARK OFFICE
CERTIFICATE OF CORRECTION

PATENT NO. : D692,396 S
APPLICATION NO. : 29/417865
DATED : October 29, 2013
INVENTOR(S) : Hashimoto et al.

Page 1 of 1

It is certified that error appears in the above-identified patent and that said Letters Patent is hereby corrected as shown below:

On the title page, Item [75] Inventors

Please change second inventor: "Kazutohi Ito, Komaki (JP)" to -- Kazutoshi Ito, Komacki (JP) --

Signed and Sealed this
Seventh Day of January, 2014

Margaret A. Focarino
Commissioner for Patents of the United States Patent and Trademark Office

UNITED STATES PATENT AND TRADEMARK OFFICE
CERTIFICATE OF CORRECTION

PATENT NO. : D692,396 S
APPLICATION NO. : 29/417865
DATED : October 29, 2013
INVENTOR(S) : Hashimoto et al.

Page 1 of 1

It is certified that error appears in the above-identified patent and that said Letters Patent is hereby corrected as shown below:

On the title page, Item [75] Inventors

Please change second inventor: "Kazutohi Ito, Komaki (JP)" to -- Kazutoshi Ito, Komaki (JP) --

This certificate supersedes the Certificate of Correction issued January 7, 2014.

Signed and Sealed this
Twenty-fifth Day of March, 2014

Michelle K. Lee
Deputy Director of the United States Patent and Trademark Office
